(57) **CLAIM**

The ornamental design for a power and data center, as shown and described.

DESCRIPTION

FIG. 1 is a top perspective view of a power and data center showing our new design in a closed configuration;

FIG. 2 is another top perspective view thereof, viewed from an opposite side;

FIG. 3 is a bottom perspective view thereof;

FIG. 4 is a top plan view thereof;

FIG. 5 is a bottom plan view thereof;

FIG. 6 is a left side elevation thereof;

FIG. 7 is a right side elevation thereof;

FIG. 8 is a front elevation thereof;

FIG. 9 is a rear elevation thereof;

FIG. 10 is another top perspective view of the power and data center in a first open configuration;

FIG. 11 is another top perspective view thereof, viewed from an opposite side;

FIG. 12 is another top perspective view thereof, viewed from an opposite end;

FIG. 13 is a bottom perspective view thereof;

FIG. 14 is a top plan view thereof;

FIG. 15 is a bottom plan view thereof;

FIG. 16 is a left side elevation thereof;

FIG. 17 is a right side elevation thereof;

FIG. 18 is a front elevation thereof;

FIG. 19 is a rear elevation thereof;

FIG. 20 is another top perspective view of the power and data center in a second open configuration;

FIG. 21 is another top perspective view thereof, viewed from an opposite side;

FIG. 22 is another top perspective view thereof, viewed from an opposite end;

FIG. 23 is a bottom perspective view thereof;

FIG. 24 is a top plan view thereof;
